GRIPPER

Fred C. Eastman, Marblehead, Mass., assignor to
United Shoe Machinery Corporation, Flemington, N. J., a corporation of New Jersey

Application July 30, 1941, Serial No. 404,589

22 Claims. (Cl. 12—11.1)

This invention relates to grippers for use in shoe machines for pulling uppers to shape them over lasts or other forms. The invention is herein illustrated as embodied in a gripper particularly designed for use in a toe-lasting machine such as disclosed in United States Letters Patent No. 2,160,846, granted on June 6, 1939, on an application of mine and A. F. Pym's, but it will be understood that it is more generally applicable to various machines.

In the machine disclosed in the above-mentioned Letters Patent each of the several grippers includes a pair of jaws which after gripping the upper maintain a grip of the same force thereon during the upper-pulling operation, the jaws being closed by spring-operated mechanism the action of which is unaffected by the pulling of the upper. While this construction has proved satisfactory under most conditions, it has been found that when an upper is unusually heavy and is subjected to a comparatively hard pull the jaws may not hold it securely enough for the best results in the upper-pulling operation. An object of the present invention, accordingly, is to provide a construction such as to increase the security with which the upper is gripped and held by the jaws without the necessity of using a jaw-closing spring which is stronger than is otherwise desirable. To this and other ends, the invention is herein illustrated as embodied in a gripper having mechanism for effecting relative movement of the jaws to grip the upper prior to the upper-pulling operation and additional mechanism for effecting further relative movement of the jaws to increase the force of their grip on the upper in the course of the upper-pulling operation. In the construction shown this additional mechanism acts in response to resistance of the upper to the force of the pull applied thereto, so that the force with which the upper is gripped increases with the force of the pull. As more particularly herein illustrated, the gripping of the upper prior to the pull is effected by a cam which is operated by the usual jaw-closing spring and acts on one of the jaws alone to move it into upper-gripping position and to lock it against reverse movement, and the increase in the force of the grip of the jaws on the upper is effected through lever mechanism which acts on the other jaw alone and is operated by relative movement of parts of the gripper resulting from resistance of the upper to the force of the pull. In addition to novel features involved in such a combination of mechanisms for effecting the gripping of the

upper and for increasing the force of the grip thereon, novel features are also to be recognized in the jaw-closing means and in the means for increasing the force with which the jaws grip the upper.

When a shoe is positioned bottom upward for the toe-lasting operation in the machine disclosed in the above-mentioned Letters Patent, the margin of the upper along the sides of the toe is likely to occupy a somewhat lower position near the end of the toe than farther heelwardly, since ordinarily the portions of the upper immediately beyond the toe-end portion have already been lasted or at least pulled over and fastened to the insole. In a further aspect, the present invention provides, for pulling the upper at each side of the toe, a gripper specially constructed in view of these conditions. To facilitate the insertion of the proper amount of upper materials in the jaws of the gripper, the jaws are arranged to extend lengthwise of the last at an inclination to the bottom of the last such that portions of the jaws located comparatively near the end of the toe extend farther toward the upper heightwise of the last than portions more remote from the end of the toe. In the construction shown, moreover, the jaws are provided with upper-engaging teeth arranged to extend lengthwise of the margin of the upper and have notches formed only in portions of the teeth which are located comparatively near the end of the toe. The portions of the teeth where the notches are located grip the upper more effectively than other portions, so that the upper is held more securely in locations where it is comparatively loose on the last than it is near the portions thereof which have already been pulled over or lasted. Since the upper near these portions need be pulled but little in the toe-lasting operation, the jaws may slip more or less thereon while maintaining a more secure grip on the portions nearer the end of the toe where a more effective pull is required.

The above and other features of the invention, including various novel details of construction and combinations of parts, will now be more particularly described with reference to the accompanying drawing and thereafter pointed out in the claims.

50 In the drawing,

Fig. 1 is a view partly in elevation and partly in vertical section of one of the side grippers of the machine shown in the above-mentioned Letters Patent as modified in accordance with the present invention;

Fig. 2 shows a portion of the same gripper in elevation, as viewed from the left with reference to Fig. 1;

Fig. 3 is a view similar to Fig. 1 of a portion of the gripper, but showing the parts as they appear when gripping and pulling an upper and showing also other portions of the machine;

Fig. 4 is a view similar to Fig. 2 of the gripper jaws, but illustrating their relation to a shoe in the pulling of the upper and showing also a portion of another one of the grippers;

Fig. 5 shows one of the jaws detached; and

Fig. 6 is a plan view illustrating how the several grippers are grouped relatively to the shoe and to toe-lasting wipers in the above-mentioned machine.

The machine shown in the above-mentioned Letters Patent is provided with three grippers for gripping the margin of the toe-end portion of the upper and for pulling the upper automatically in time relation to the operation of wipers 2 which, after the pulling of the upper, wipe its marginal portion inwardly over the insole into lasted position, as shown in Fig. 6, the last and shoe being held by a toe rest 4 (Fig. 4) in a position determined by an insole-engaging plate 6 (Figs. 3 and 6). The grippers comprise a toe-end gripper 8 for pulling the upper at the end of the toe and opposite side grippers 10 arranged to act on the upper at the sides of the toe. The present drawing shows, by reference to details of the left-hand side gripper, how each of the two side grippers may be modified for purposes of this invention, and it is contemplated that the toe-end gripper 8 will in most respects be similarly modified in a manner which will be obvious from the description of the side gripper construction.

The side gripper 10 shown in Figs. 1, 2 and 3 includes a pair of upper-gripping jaws 12 and 14 supported by a tubular casing 16 which corresponds to the casing 400 shown in the previously mentioned Letters Patent. The jaws, however, are not supported directly on the casing, as heretofore, but on a jaw carrier 18 having a tubular portion 20 extending upwardly into an enlarged lower end portion of the casing and loosely mounted therein to permit relative vertical movements of the jaw carrier and the casing between limits determined by a pin 22 mounted in the casing and a slot 24 formed in the tubular portion 20 of the jaw carrier. The purpose of this construction will be hereinafter described. Clamped on the casing 16 are members 26 and 28 through which upward movement is imparted to the gripper to pull the upper heightwise of the last, these members corresponding to the members 524 and 526 shown in the above-mentioned Letters Patent. Within the casing is a jaw-closing rod 30 similar to a corresponding rod of the prior construction and arranged to be moved upwardly by a spring 32 to effect relative movement of the jaws to grip the upper, this spring acting on the lower end of a tubular plunger 34 which is slidably mounted on the upper end of the rod and carries a pin 36 extending through a slot 38 in the rod. It will be understood that in moving the rod upwardly the pin engages it at the upper end of the slot. In the construction herein shown the lower end of the spring 32 is seated on the jaw carrier 18. When the jaws are in open relation the rod 30 is held depressed as heretofore by a member 40 in engagement with the upper end of the plunger 34, the plunger acting yieldingly on the rod through the pin 36 and a light

spring 42 in the rod. The member 40 corresponds to the member 452 shown in the above-mentioned Letters Patent.

In the construction herein shown both the jaws 12 and 14 are mounted to swing about a pin 44 supported by the lower ends of two downwardly extending plates 46 which are formed on the jaw carrier 18 in spaced relation to each other. The gripping of the upper in response to the upward movement of the rod 30 is effected by swinging movement of the jaw 12, which engages the outer face of the upper, toward the jaw 14. For this purpose, in the construction herein shown, an upwardly extending tail portion 48 of the jaw 12 is engaged by a cam 50 rotatably mounted on a pin 52 supported by the plates 46 of the jaw carrier 18 and parallel to the pin 44. This cam is provided with a recess 54 to receive the tail portion of the jaw when the latter is in its open position, as illustrated in Fig. 1, and with a peripheral face 56 for engaging the tail portion of the jaw to impart to the jaw the latter portion of its swinging movement. This peripheral face of the cam is in such relation to the axis 25 of the pin 52 that when the jaw 12 is in upper-gripping position, as shown in Fig. 3, the cam serves to lock it effectively against any reverse swinging movement. For rotating the cam thus to operate the jaw 12 the rod 30 is connected to the cam by a pair of links 58 between which the tail portion 48 of the jaw lies when the jaws are in open relation. For returning the jaw 12 to open position there is provided a link 60 pivotally connected to the cam 50 and having therein a slot 62 in which lies a pin 64 carried by the tail portion 48 of the jaw. By reference to Figs. 1 and 3 it will be evident that this slot permits the link to move idly during a portion of the return movement of the cam 50 and that the cam acts thereafter through the link to swing the jaw 12 to its fully open position.

When the jaw 12 is swung as above described to grip the upper, no corresponding movement of the jaw 14 toward the jaw 12 takes place, and, accordingly, the gripping of the upper is effected by the movement of the jaw 12 alone. The jaw 14, however, is not fixed to the jaw carrier 18, but as previously suggested is capable of swinging about the pin 44. For controlling the jaw 14 there are provided two levers 66 mounted at the outer sides of the plates 46 of the jaw carrier 18 to swing about the previously mentioned pin 52, the right-hand ends of these levers, as the parts are viewed in Figs. 1 and 3, being connected by links 68 to the jaw 14. Only one of these links is visible in the drawing, since they lie in the same vertical planes as the plates 46 of the jaw carrier. The other ends of the levers 66 are connected by links 70 to the previously mentioned pin 22 which is mounted in the casing 16. It will thus be seen that no swinging movement of the jaw 14 about the pin 44 can take place except as accompanied by relative vertical movement of the casing 16 and the jaw carrier 18. In the pulling of the upper heightwise of the last, as more fully hereinafter explained, there is a tendency to move the casing upward relatively to the jaw carrier and thereby to move the jaw 14 toward the jaw 12 to increase the force with which the upper is gripped by the jaws. It will be understood that the two levers 66 have a single function, the duplicate construction being provided simply for greater strength and better balance.

By reference to Fig. 4 it will be observed that

the jaws of the gripper are inclined somewhat relatively to the bottom of the last in a downward direction toward the end of the toe. The reason for this construction is that when a shoe is presented to the machine the margin of the upper which is to be engaged by the gripper at each side of the toe usually occupies a position somewhat lower near the end of the toe than farther heelwardly, as hereinbefore explained. The inclination of the jaws in the manner illustrated facilitates the insertion of the proper amount of upper in the jaws throughout the length of the jaws. It will also be observed by reference particularly to Figs. 1 and 5 that the jaw 14 is provided with two teeth 72 arranged to extend lengthwise of the margin of the upper and that the jaw 12 has a single similarly extending tooth 74 arranged to force the upper into the space between the two teeth 72. In portions of the several teeth which are located comparatively near the end of the toe there are provided notches 76 which increase the effectiveness of the grip of those portions of the teeth on the upper as compared with the portions which are without such notches. Accordingly, the gripper holds the upper more securely in locations where it is comparatively loose on the last prior to the toe-lasting operation than adjacent to portions of the upper which have already been pulled over or lasted and where, therefore, but little further pull is required.

The manner of operation of the novel gripper will now be briefly summarized. Initially the member 40 is in the position illustrated in Fig. 1 and holds the jaw-closing rod 30 depressed with the jaws of the gripper in open relation, the jaw carrier 18 being held by this member, through the spring 32, in its lowest position determined by engagement of the pin 22 with the tubular portion 20 of the carrier at the upper end of the slot 24. It will be understood that at this time the gripper jaws occupy a lower position than in Fig. 4, their downward inclination toward the end of the toe being such as to facilitate the insertion of the proper amount of upper materials between them near the end of the toe as well as in other locations. When in the operation of the machine the member 40 is moved upwardly and the jaw-closing rod 30 is accordingly lifted by the spring 32, the rod acts through the links 58 to swing the cam 50 from its starting position (Fig. 1) to the position in which it is shown in Fig. 3, the cam acting on the tail portion 48 of the jaw 12 to swing this jaw toward the jaw 14 into position to grip the upper. Near the end of its movement the jaw 12 by its pressure on the margin of the upper causes the jaw 14 to swing a short distance in the same direction as the jaw 12. The effect of this movement of the jaw 14 is to swing the levers 66 about their connections with the links 70 and thus to lift the jaw carrier 18 relatively to the casing 16 to space the upper end of the slot 24 from the pin 22. This action is facilitated by reason of the fact that after the upward movement of the member 40 away from the plunger 34 there is no longer any tendency to force the jaw carrier 18 in a downward direction relatively to the casing 16 through the spring 32. Thereafter, in the course of the operation of the machine, the members 26 and 28 are moved upwardly to move the casing 16 also upwardly and thus to cause the gripper to pull the upper heightwise of the last. In this operation upper-pulling force is transmitted from the casing 16

5 to the jaw carrier 18 through the links 70 and the levers 66 connected by the links 68 to the jaw 14, and in so far as this force is effective to lift the jaw carrier it is also effective on the jaw 14 to increase the force with which the upper is gripped by the jaws, the jaw 12 being held positively by the cam 50 against reverse movement. In other words, the mechanism connecting the casing 16 to the jaw 14 acts in response to resistance of the upper to the force of the pull applied thereto, by reason of the tendency of the casing to move upward relatively to the jaw carrier 18, to increase the force with which the upper is gripped by the jaws. Accordingly, insurance is afforded that if an upper is unusually heavy and is subjected to a comparatively hard pull the jaws will hold it securely enough for satisfactory results in the lasting operation. By reason of the construction of the jaws, however, they may slip more or less near the end of the upper-pulling operation on portions of the upper comparatively remote from the end of the toe while maintaining a more effective grip on portions located nearer the end of the toe, as hereinbefore explained.

Having described the invention, what I claim as new and desire to secure by Letters Patent of the United States is:

1. In a shoe machine, a gripper having a pair of jaws for gripping an upper between them and for pulling the upper, said gripper including jaw-closing mechanism for effecting relative movement of said jaws to grip the upper prior to the upper-pulling operation and including also additional mechanism for thereafter effecting further relative movement of the jaws in the course of the upper-pulling operation to increase the force of their grip on the upper.

2. In a shoe machine, a gripper having a pair of jaws for gripping an upper between them and for pulling the upper, said gripper including jaw-closing mechanism for effecting relative movement of said jaws to grip the upper prior to the upper-pulling operation and including also additional mechanism arranged to act thereafter in response to resistance of the upper to the force of the pull applied thereto to effect further relative movement of the jaws to increase the force of their grip on the upper.

3. In a shoe machine, a gripper having a pair of jaws for gripping an upper between them and for pulling the upper, said gripper including a jaw carrier supporting said jaws, means supported on said jaw carrier for effecting relative movement of the jaws to grip the upper prior to the upper-pulling operation, and additional means also supported on said jaw carrier for thereafter effecting further relative movement of the jaws in the course of the upper-pulling operation to increase the force of their grip on the upper.

4. In a shoe machine, a gripper having a pair of jaws for gripping an upper between them and for pulling the upper, said gripper including parts relatively movable in response to resistance of the upper to the force of the pull applied thereto, mechanism for effecting relative movement of said jaws to grip the upper prior to the upper-pulling operation, and additional mechanism arranged to be operated by the relative movement of said parts in the course of the upper-pulling operation to effect further relative movement of the jaws to increase the force of their grip on the upper.

5. In a shoe machine, a gripper having a pair

of jaws for gripping an upper between them and for pulling the upper, means for moving one of said jaws alone toward the other jaw to grip the upper prior to the upper-pulling operation, and additional means for thereafter moving said other jaw alone toward the first-named jaw in the course of the upper-pulling operation to increase the force with which the upper is gripped by the jaws.

6. In a shoe machine, a gripper having a pair of jaws for gripping an upper between them and for pulling the upper, means for moving one of said jaws alone toward the other jaw to grip the upper prior to the upper-pulling operation, and mechanism arranged to act thereafter in response to resistance of the upper to the force of the pull applied thereto to move said other jaw toward the first-named jaw and thus to increase the force with which the upper is gripped by the jaws.

7. In a shoe machine, a gripper having a pair of jaws for gripping an upper between them and for pulling the upper, mechanism for moving one of said jaws alone toward the other jaw to grip the upper and for locking it positively against reverse movement, and additional mechanism arranged to act thereafter in response to resistance of the upper to the force of the pull applied thereto to move said other jaw toward the first-named jaw and thus to increase the force with which the upper is gripped by the jaws.

8. In a shoe machine, a gripper having a pair of jaws for gripping an upper between them and for pulling the upper, a cam arranged to act on one of said jaws alone to move it toward the other jaw to grip the upper and then to hold it against reverse movement, and mechanism arranged to act thereafter in the course of the upper-pulling operation to move the other jaw toward said cam-operated jaw and thus to increase the force with which the upper is gripped by the jaws.

9. In a shoe machine, a gripper having a pair of jaws for gripping an upper between them and for pulling the upper, a jaw carrier supporting said jaws, means supported on said jaw carrier for moving one of the jaws alone toward the other jaw to grip the upper prior to the upper-pulling operation, and additional means also supported on said jaw carrier for thereafter moving said other jaw toward the first-named jaw in response to resistance of the upper to the force of the pull applied thereto to increase the force with which the upper is gripped by the jaws.

10. In a shoe machine, a gripper having a pair of jaws for gripping an upper between them and for pulling the upper, said gripper including a jaw carrier supporting said jaws, a cam rotatably supported on said jaw carrier and arranged to act on one of said jaws to move it toward the other jaw to grip the upper, spring-operated means for thus operating said cam prior to the upper-pulling operation, and mechanism also supported on said jaw carrier for thereafter moving said other jaw toward the cam-operated jaw in the course of the upper-pulling operation to increase the force with which the upper is gripped by the jaws.

11. In a shoe machine, a gripper having a pair of jaws for gripping an upper between them and for pulling the upper, said gripper including parts relatively movable in response to resistance of the upper to the force of the pull applied thereto, mechanism for moving one of said jaws alone toward the other jaw to grip the upper prior to the upper-pulling operation, and addi-

tional mechanism arranged to be operated by the relative movement of said parts in the course of the upper-pulling operation to move said other jaw toward the first-named jaw to increase the force with which the upper is gripped by the jaws.

12. In a shoe machine, a gripper having a pair of jaws for gripping an upper between them and for pulling the upper, said gripper including a jaw carrier supporting said jaws and also a member supporting said jaw carrier, said carrier and member being relatively movable in response to resistance of the upper to the force of the pull applied thereto, means supported on said jaw carrier for effecting relative movement of the jaws to grip the upper prior to the upper-pulling operation, and additional means also supported on the jaw carrier and connected to said member for thereafter moving one of the jaws toward the other to increase the force of their grip on the upper in response to the relative movement of said carrier and member in the upper-pulling operation.

13. In a shoe machine, a gripper having a pair of jaws for gripping an upper between them and for pulling the upper, said gripper including a jaw carrier supporting said jaws and also a member supporting said jaw carrier, said carrier and member being relatively movable in response to resistance of the upper to the force of the pull applied thereto, a cam supported on said jaw carrier for moving one of the jaws toward the other to grip the upper prior to the upper-pulling operation, a lever also supported on said jaw carrier and connected to said other jaw, and means connecting said lever and member for operating the lever to move said other jaw toward the first-named jaw to increase the force with which the upper is gripped by the jaws in response to the relative movement of said carrier and member in the upper-pulling operation.

14. In a shoe machine, a gripper having a pair of jaws for gripping an upper between them and for pulling the upper, said gripper including members relatively movable in response to resistance of the upper to the force of the pull applied thereto and on one of which members the jaws are supported, a lever supported on said last-named member for moving one of the jaws toward the other to increase the force with which the upper is gripped by the jaws, and means for thus operating said lever by the relative movement of said members in the upper-pulling operation.

15. In a shoe machine, a gripper having a pair of jaws for gripping an upper between them and for pulling the upper, said gripper including members relatively movable in response to resistance of the upper to the force of the pull applied thereto and on one of which members the jaws are supported, a lever fulcrumed between its opposite ends on said last-named member, a link connecting one end of said lever to one of the jaws for moving that jaw toward the other by the lever to increase the force with which the upper is gripped by the jaws, and a link connecting the other end of the lever to the other member for thus operating the lever by the relative movement of said members in the upper-pulling operation.

16. In a shoe machine, a gripper having a pair of jaws for gripping an upper between them and for pulling the upper, a member on which said jaws are supported, a cam rotatably supported on said member for moving one of the jaws to-

ward the other to grip the upper by engagement of the cam with the jaw thus moved, and a spring-operated member for rotating said cam.

17. In a shoe machine, a gripper having a pair of jaws for gripping an upper between them and for pulling the upper, a member on which said jaws are supported, a cam rotatably supported on said member for moving one of the jaws toward the other to grip the upper, a spring-operated rod, and a link connecting said rod to the cam 10 for rotating the cam by the rod.

18. In a shoe machine, a gripper having a pair of jaws for gripping an upper between them and for pulling the upper, a member on which said jaws are supported, a cam rotatably supported on said member for swinging one of the jaws toward the other to grip the upper by rotation of the cam about an axis substantially parallel to the axis of the swinging jaw, and spring-operated means for thus rotating said cam.

19. In a shoe machine, a gripper having a pair of jaws for gripping an upper between them and for pulling the upper, a jaw carrier supporting said jaws and movable with them to pull the upper, a cam supported on said jaw carrier for rotation to move one of the jaws toward the other to grip the upper, and a spring arranged thus to rotate said cam and movable thereafter bodily with the jaws in the pulling of the upper.

20. In a shoe machine, the combination with 30 means for positioning a last and shoe for the lasting of the toe-end portion of the upper, of

grippers for gripping and pulling the upper at the opposite sides of the toe respectively, each of said grippers having a pair of upper-gripping jaws arranged to extend lengthwise of the last at such an inclination to the bottom of the last as to cause portions of the jaws which engage the upper comparatively near the end of the toe to extend farther toward the upper heightwise of the last than portions of the jaws more remote from the end of the toe.

21. In a shoe machine, the combination with means for positioning a last and shoe for the lasting of the toe-end portion of the upper, of grippers arranged to pull the upper at the opposite sides of the toe respectively and each having a pair of jaws for gripping the upper between them, portions of said jaws which are located comparatively near the end of the toe being so formed as to grip the upper more securely than portions more remote from the end of the toe.

22. In a shoe machine, the combination with means for positioning a last and shoe for the lasting of the toe-end portion of the upper, of grippers arranged to pull the upper at the opposite sides of the toe respectively and each having a pair of jaws for gripping the upper between them, said jaws being provided with upper-engaging teeth extending lengthwise of the margin of the upper and the teeth having notches formed only in portions thereof which are located comparatively near the end of the toe.

FRED C. EASTMAN.
